(57) **CLAIM**

The ornamental design for a beverage container, as shown and described.

DESCRIPTION

FIG. 1 is a front view of a beverage container, showing my new design;

FIG. 2 is a perspective view thereof;

FIG. 3 is a front exploded perspective view thereof;

FIG. 4 is a bottom exploded perspective view thereof;

FIG. 5 is a top view of FIG. 1; and,

FIG. 6 is a bottom view thereof.

The broken lines in the drawing depict portions of the beverage container that form no part of the claimed design.
